UNITED STATES PATENT OFFICE.

HENRY HERMAN SCHOTT, OF NORTH YAKIMA, WASHINGTON.

SEAT ATTACHMENT.

No. 910,589.

Specification of Letters Patent.

Patented Jan. 26, 1909.

Application filed May 19, 1908. Serial No. 433,734.

To all whom it may concern:

Be it known that I, HENRY HERMAN SCHOTT, a citizen of the United States, residing at North Yakima, in the county of Yakima and State of Washington, have invented new and useful Improvements in Seat Attachments, of which the following is a specification.

My invention pertains to seat attachments; and it has for its object to provide a simple and inexpensive device designed to be fixed on the back of a theater or church seat and to hold articles of various descriptions.

The invention will be fully understood from the following description and claim when the same are read in connection with the drawings, accompanying and forming part of this specification, in which:

Figure 1 is a perspective view illustrating the device constituting the preferred embodiment of my invention. Fig. 2 is a view showing a seat back in section and my novel device in proper position thereon.

Referring by letter to the said drawings, A is the back of a church or other seat, and B is my novel device which is designed to be fixed on the rear side of the back A by screws a, after the manner shown in Fig. 2.

The device B is preferably, though not necessarily, formed of a single piece of finely-tempered spring steel, and comprises an intermediate, flat body portion b in which are apertures c for the passage of the screws a,

outwardly bowed arms d reaching upward from the ends of the body portion b, and a tongue e reaching downward from the body and having an outwardly bowed upper portion f and a hook g at the lower end thereof.

It will be manifest from the foregoing that when the device is attached to a seat back, as shown in Fig. 2, cards and other articles,

umbrellas for instance, may be interposed between the seat back and the arms d to be clamped and held by the latter. It will also 45 be manifest that the brim of a stiff hat may be interposed between the outwardly bowed portion f of the tongue e to enable the tongue to support the hat, while articles of various kinds may be conveniently hung on the 50 hook g.

It will be gathered from the foregoing that my novel seat attachment is simple and inexpensive and is adapted to be expeditiously and easily connected to the back of a seat 55 without the employment of skilled labor and without the employment of any tool other than an ordinary screw driver.

Having described my invention, what I claim and desire to secure by Letters-Pat- 60 ent, is:

As a new article of manufacture, a device formed of a single piece of resilient sheet metal and consisting essentially of a horizontal, flat body portion in which are a 65 plurality of apertures for the passage of screws, outwardly bowed arms reaching upwardly from the ends of the body portion and adapted to bear adjacent to their upper ends against a seat back and terminating at 70 said ends in outwardly directed portions, and a tongue depending from the body portion and having an outwardly bowed portion and also having a hook at the lower end of said portion, adapted to bear against the seat 75 back and support articles of various kinds.

In testimony whereof I have hereunto set my hand in presence of two subscribing witnesses.

HENRY HERMAN SCHOTT.
